UNITED STATES PATENT OFFICE.

LOTHAR VON GRAVE, OF WALLINGFORD, CONNECTICUT, ASSIGNOR TO THE H. L. JUDD & COMPANY, OF NEW YORK, N. Y.

DESIGN FOR A LAMP-FOUNT HOLDER.

SPECIFICATION forming part of Design No. 23,420, dated July 3, 1894.

Application filed June 7, 1894. Serial No. 513,826. Term of patent 3½ years.

To all whom it may concern:

Be it known that I, LOTHAR VON GRAVE, a subject of the Emperor of Germany, residing at Wallingford, New Haven county, in the State of Connecticut, have invented and produced a new and original Design for a Lamp-Fount Holder, of which the following is a specification, reference being had to the accompanying drawing, wherein the figure is a side view of a lamp-fount holder embodying my design.

The essential features of my design consist in a lamp fount holder of openwork formation, wherein there are grille-like portions connecting with ornamental scroll-like portions having garlands interlaced therewith.

In the drawing, A designates the lamp fount holder of openwork formation wherein grille-like portions a are connected to scroll-like portions b which have garlands c interlaced or connecting therewith.

What I claim is—

The design for a lamp fount holder, substantially as herein shown and described.

LOTHAR VON GRAVE.
